BASE CLEANER

Filed Nov. 1, 1938

UNITED STATES PATENT OFFICE

2,162,955

BASE CLEANER

Moses Liebmann, New York, N. Y.

Application November 1, 1938, Serial No. 238,185.

9 Claims. (Cl. 273—25)

This invention relates to means for dusting or cleaning the base or "home plate" such as is used in baseball games, and has for its object the provision of means by which the "home plate" may 5 be speedily and automatically cleaned or dusted as required, without requiring manual effort on the part of the umpire or players.

At the present time, playing the game causes the home plate to periodically become covered 10 with and obscured by dust and dirt, this requiring the umpire, and often the players, to occasionally dust off the plate with a whisk broom or the like so that it will be plainly visible. By means of the present invention, the plate 15 may be easily and automatically cleaned by merely operating a valve to cause an air blast to eject the dust and dirt from the top of the plate, thus greatly simplifying the game and lessening the duties of the umpire.

20. In the accompanying drawing, wherein an embodiment of the invention is disclosed, Fig. 1 is a plan view of a structure constructed in accordance with the invention; Fig. 2 is a sectional view on the line 2—2 of Fig. 1, looking in the direction of the arrows; Fig. 3 is a sectional view 25 similar to that of Fig. 2, except that it shows the base-cleaning device in operative or working position; Fig. 4 is a sectional view on the line 4—4 of Fig. 2, looking in the direction of the arrows; Fig. 5 is a sectional view through the air valve, and Fig. 6 is a sectional view of a modified structure.

With reference to the structure shown in Figs. 1 to 5 inclusive, 7 indicates the base, or so-called "home plate" as employed on a baseball diamond. 35 The base generally comprises a section of flat material such as rubber or the like and it is provided with a flat upper face 8 which is generally disposed to lie substantially flush with the surface of the diamond, the plate being embedded or otherwise anchored in the ground. During the playing of the game, dust and dirt accumulates 40 on the top or upper flat face 8 of the plate, thus obscuring the plate from the view of the players and umpire. Accordingly, it then becomes necessary for the umpire to dust off the dirt and dust from the base, which he usually does by stooping down and using a whisk broom. By the structure now to be described such manual effort on the part of the umpire is dispensed with.

50. Situated directly behind the plate, or at one of the other edges thereof if preferred, is a receptacle or casing 9 embedded in the ground with its top disposed flush with the surrounding ground surface. The casing is firmly anchored in position by being embedded in a block of concrete 10, or else held immovably in any other equivalent manner. The upper portion of the receptacle 55 acts as a guide for an air manifold 11 which is mounted for movement up and down in the upper

part of the receptacle. An elongated slot 12, or a series of small slots or holes, is formed in the manifold, with the open ends of said slots or holes directed toward the base, as clearly seen in Figs. 2 and 3. Extending downwardly from the lower portion of the hollow manifold 11 is a number of nipples or short pipes 13 which project into the ends of tubular extensions 14 formed on an air-supply pipe 15. The manifold is provided with several loop members 16 to which are attached the springs 17 having their lower ends secured to loops 18 attached to supports 19 in which the pipe 15 is mounted and which extend upwardly from the bottom of the receptacle 9. The springs 17 exert a downward pull upon the manifold, and hold it in a normally lowered or retracted position, as shown in Figs. 2 and 4, with its upper face flush or even slightly below the surrounding ground surface.

The air-supply pipe 15 extends under ground 20 to a source of compressed air, such as the tank 20, which is connected by the pipe 21 to an air compressor 22 actuated by the electric motor 23 or other source of power. These elements may be situated remotely from the home plate, such as by being located under the grand stand or at any other convenient position, and the tank 20, wherever situated, is connected to the manifold 11 by the line of piping 15 extending under ground and thus concealed, as well as protected 30 from damage.

Interposed in the pipe line 15 is a valve casing 24 enclosing the valve 26, normally held closed by means of a spring 28, to shut off communication between the manifold 11 and the tank 20. 35 Valve 26 is provided with an upwardly projecting stem 27 which extends in the tubular guide 28 and is adapted to be depressed, when desired, by a plunger 30 terminating at its upper end in a head or button 31. The valve and the actuating plunger are located conveniently to the 40 umpire, yet so disposed as to be completely out of the way of the players. The plunger 30 and attached button 31 are removable as a unit out of the guide 28 when desired to prevent unauthorized operation of the valve or tampering with it at times when a game is not in progress.

45. From the foregoing, the operation of the device will be readily understood. When the base becomes obscured by dust and dirt accumulated on top of it during the playing of the game, the umpire need merely depress the button 31 with his foot to at once cause the plate to become cleaned. Valve 26, becoming opened by the foot pressure, will permit the rush of air under pressure through pipe 15 into the manifold 11 through the nipples 13. The air pressure thus created within the manifold will raise or lift the manifold until the collars 32 on the nipples 13 abut against the stops 33. At this point the slot 50

12 (or series of openings) will have its outlet raised above the upper face of the plate 7, as indicated in Fig. 3, and the blast of air emanating from the outlet 12 will be directed across the top of the plate and will blow the dust and dirt therefrom. As soon as pressure of the foot on the button 31 is released, valve 26 will close and the flow of air from tank 20 will cease, whereupon the pressure in manifold 11 will be lowered and the springs 17 will draw the manifold down to its retracted or lowered position shown in Figs. 2 and 4. Should rain water trickle down into the receptacle 9 it will drain out through opening 35 provided in the bottom of the receptacle 9, and seep into the soil below the receptacle.

In the modified structure shown in Fig. 6, the base or home plate is in the form of a perforated member having a plurality of holes or apertures 37 comprising air blast openings and communicating with a chamber 38 embedded in the ground below the base and provided with a plurality of openings 39 in registration with those indicated at 37 in the base. Chamber 38 is formed with an extended nipple portion 40 coupled to the end of the pipe line 15. With this structure, when the valve 26 is opened, as heretofore explained, the air blast will be directed through the aligned openings 37 and 39 and will blow the dust and dirt from the top of the base. Any dirt falling down into the chamber 38 will be blown out through the openings by the next air blast.

It will be clear that by the means shown, the base may be readily cleaned of dust and dirt by mere foot pressure on the valve-actuating plunger so that the constant manual effort on the part of the umpire now required will be completely eliminated.

40. What I claim is:

1. A base cleaner comprising an air nozzle mounted in the ground near the base to be cleaned, said nozzle having an air blast opening normally maintained below the level of the upper face of the base and directed toward the base and adapted to be raised to bring said opening adjacent the top of the base, and a source of air under pressure connected to the nozzle and adapted to direct an air blast through the opening therein to cause said air blast to blow dust and dirt off the top of the base.

2. A base cleaner comprising comprising an air nozzle mounted in the ground near the base to be cleaned, said nozzle having an air blast opening directed toward the base and mounted to permit of it being raised to bring said opening adjacent the top of the base, a source of air under pressure connected to the nozzle and adapted to direct an air blast through the opening therein to cause said air blast to blow dust and dirt off the top of the base, and a manually-operated valve interposed between the nozzle and the source of air for controlling the flow of air from its source to the nozzle.

65. 3. A base cleaner comprising, a housing situated adjacent to the base to be cleaned, a nozzle member within said housing, said nozzle having an air blast opening, means for normally holding the nozzle retracted within the housing and its air blast opening covered thereby, and means for moving the nozzle out of the housing to expose the air blast opening and direct an air blast

therethrough and over the surface of the base to clean the same.

4. A base cleaner comprising, a housing located in the ground adjacent the base to be cleaned, a nozzle member within said housing and having its upper end substantially flush with the upper surface of the base, said nozzle having an air blast opening normally covered by a portion of the housing and normally maintained in a position below the upper face of the base, means for normally holding the nozzle retracted within the housing, and means for moving the nozzle out of the housing to expose its air blast opening above the surface of the base, said means comprising air under pressure which is directed through the raised nozzle and out of its air blast opening and over the upper surface of the base to clean the same.

5. A base cleaner comprising, a movable nozzle having an air blast opening located near the base to be cleaned, means for directing an air blast through the nozzle and air blast opening, means for controlling the flow of air to the nozzle and means for closing the air blast opening when the flow of air to the nozzle is shut off.

6. A base cleaner comprising, a movable nozzle having an air blast opening located near the base to be cleaned, means for directing an air blast through the nozzle and air blast opening and over the surface of the base to clean the same, and means for closing the air blast opening when flow of air to the nozzle is shut off, said last-mentioned means comprising a housing into which the nozzle is moved and which extends over and closes the air blast opening when the nozzle is moved into it, and means for moving the nozzle into said housing when the flow of air to the nozzle is shut off.

7. A base cleaner comprising, an air nozzle near the base to be cleaned and normally held out of base-cleaning position, and means for supplying air under pressure to cause the nozzle to be moved by said air pressure into base-cleaning position relative to the base and to eject an air blast over the top of the base.

8. A base cleaner comprising, an air blast nozzle member located adjacent to the top surface of a base to be cleaned and normally maintained out of base-cleaning position, a source of air blast connected to said nozzle, means for moving the nozzle to a position whereby it will direct an air blast over the upper face of the base, and means for controlling the air flow from the source to the nozzle.

9. A base cleaner comprising a receptacle disposed in the ground near the base to be cleaned, a blast nozzle mounted for raising movement under air pressure and for lowering movement in said receptacle, means for normally holding said nozzle in a lowered position in said receptacle, a source of compressed air connected to said nozzle and adapted to force air into the nozzle to cause the air pressure exerted therein to impinge against the interior of said nozzle to raise said nozzle out of the receptacle, the nozzle being provided with an air outlet opening which is exposed toward the base when the nozzle is raised by the air pressure and out of which the air blast is directed during the time that the nozzle is raised, and valve means for controlling the flow of air from its source to the nozzle.

MOSES LIEBMANN.
